UNITED STATES PATENT OFFICE.

HERBERT GLEN IRWIN, OF SPUR, TEXAS.

VACUUM-ENERGIZED MAKE-AND-BREAK SPARK-PLUG.

1,268,719.

Specification of Letters Patent. Patented June 4, 1918.

Application filed July 26, 1917. Serial No. 162,939.

To all whom it may concern:

Be it known that I, HERBERT G. IRWIN, a citizen of the United States, residing at Spur, in the county of Dickens and State 5 of Texas, have invented certain new and useful Improvements in Vacuum-Energized Make-and-Break Spark-Plugs; and he does hereby declare the following to be a full, clear, and exact description of the invention, such as will enable others skilled in the art to which it appertains to make and use the same, reference being had to the accompanying drawings, and to the letters and figures of reference marked thereon, which 10 form a part of this specification.

This invention relates to new and useful improvements in ignition apparatus for internal combustion engines and consists essentially in the provision of a vacuum operated make and break ignition device.

The invention consists further in the provision of an apparatus of this nature designed for use in igniting gasolene, distilled benzol and various liquid hydro-carbonated fuels having high boiling points.

The invention consists further in the provision of a device of this nature having various details of construction, combinations and arrangements of parts which will be hereinafter fully described, shown in the accompanying drawings and then specifically defined in the appended claims.

My invention is illustrated in the accompanying drawings, which with the letters of reference marked thereon, form a part of this specification and in which:

Figure 1 is a sectional view through a vacuum operated make and break spark plug.

Fig. 2 is a sectional view showing parts in plan view.

Fig. 3 is a bottom view of the contact points.

Reference now being had to the details of the drawings by numerals:

1 designates a plug, preferably of cylindrical shape, provided with a flange and made of any suitable material and adapted to hold a lubricant. Mounted within the 50 plug is a guide member 7 longitudinally apertured and in which an oscillating electrode 3 is mounted. Tubes, designated by numerals 5 and 6, of any suitable non-conducting or insulating material, are mounted

within the plug and within the tube 6 is 55 mounted a stationary electrode tube, the upper end of which is threaded and carries a binding nut 11. A spring 10 is fastened at one end to the guide member 7 and its other end is fastened to an arm 8 having 60 an angular outlined opening receiving a similarly shaped portion at the upper end of the electrode 3. Said arm is pivotally connected to a link 14 which is fastened to the diaphragm 13, which is mounted with 65 in the casing 4 having an opening therein in which one end of the flexible pipe 15 is fastened and in turn is adapted to be connected to the distributor or timing device, not shown. A suitable housing, or casing 70 9 incloses the electrode and the working parts of the device.

The vacuum operated spark plug is adapted to be placed within the cylinder of a motor. A vacuum in the intake pipe or manifold is conducted through the flexible tube to each plug by way of a distributor or timing device mechanically driven in the usual way in ignition devices. A wire cable is 75 adapted to connect all of the stationary electrodes together by way of a terminal connection on each stationary electrode. An electric current may pass down said cable and through the electrode points on engine whenever said electrode points come 80 together.

In operation the vacuum from the intake manifold acts upon the diaphragm causing the latter to move inward and by the mechanical connections described with the oscillating electrode, the latter is rocked, which will cause the angled end of the electrode 3 to contact with the projecting end of the stationary electrode, thus forming a circuit for an electric current. When the 85 vacuum is released by the distributor or timing device the said spring 10 acting against it, the diaphragm will return the latter to its normal position and the electrodes will separate breaking contact and in 90 the event of the electric current flowing through the points at the time would cause an electric arc between the points, producing the desired ignition.

While I have shown and described a particular form of mechanical apparatus, illustrating the operation of my invention, it will be understood that the construction of the

same may vary as to details in different ways without in any way departing from the spirit of the invention.

What I claim to be new is:

- 5 1. A vacuum energized make and break ignition device, comprising a cylindrical hollow plug, a stationary electrode mounted in suitable insulation, and an oscillating electrode suitably mounted within the plug,
  - 10 10 a vacuum actuated diaphragm, connections to cause the electrodes to contact with each other, a spring fastened to the oscillating electrode and adapted to return the same to its normal position.
  - 15 15 2. A vacuum energized make and break ignition device, comprising a cylindrical hollow plug, a stationary electrode mounted in suitable insulation, and an oscillating electrode suitably mounted within the plug, a
  - 20 20 vacuum actuated diaphragm, a link connected to the diaphragm, an arm movable with the oscillating electrode and pivotally connected to said link, a spring fastened at one end to said arm and its other end held sta-
  - 25 25 tionary, as set forth.
  - 30 3. A vacuum energized make and break ignition device, comprising a hollow cylindrical plug with openings in the bottom thereof, an insulating member mounted within the plug, a stationary electrode mounted in said tube and passing through one of the apertures in the plug, an oscillating electrode, and guide within the plug in which the same is mounted, said oscillat-
  - 35 35 ing electrode having a laterally projecting
- portion, an arm fixed to said oscillating electrode, a spring fastened at one end to said arm and its other end to said guide, a vacuum casing, a diaphragm mounted therein, and a link fastened to said diaphragm and having a pivotal connection to said arm, a flexible tube fastened in an opening in the casing, as set forth.
4. A vacuum energized make and break ignition device, comprising a hollow cylindrical plug with openings in the bottom thereof, an insulating member mounted within the plug, a stationary electrode mounted in said tube and passing through one of the apertures in the plug, an oscillating electrode, and guide within the plug in which the same is mounted, said oscillating electrode having a laterally projecting portion, an arm fixed to said oscillating electrode, a spring fastened at one end to said arm and its other end to said guide, a vacuum casing, a diaphragm mounted therein, and a link fastened to said diaphragm and having a pivotal connection to said arm, a flexible tube fastened in an opening in the casing, and a housing fitted over the electrodes and through which the stationary electrode passes, as set forth.

In testimony whereof I hereunto affix my signature in presence of two witnesses.

HERBERT GLEN IRWIN.
